UNITED STATES PATENT OFFICE.

ALFRED C. O. BOCK, OF BROOKLYN, NEW YORK, ASSIGNOR TO THE YALE & TOWNE MANUFACTURING COMPANY, OF STAMFORD, CONNECTICUT.

LOCK.

1,381,395.

Specification of Letters Patent. Patented June 14, 1921.

Application filed September 3, 1920. Serial No. 408,008.

To all whom it may concern:

Be it known that I, ALFRED C. O. Bock, a subject of Germany, and a resident of Brooklyn, in the county of Kings and State 5 of New York, have invented certain new and useful Improvements in Locks; and I do hereby declare the following to be a full, clear, and exact description of the invention, such as will enable others skilled in the 10 art to which it appertains to make and use the same.

My invention relates to an improvement in locks, the object being to provide a lock with bolt mechanism constructed to interlock with the strike plate or keeper so as to prevent a separation of these parts by jimmying or otherwise, and it consists in the 15 parts and combination of parts as will be more fully explained and pointed out in the 20 claims.

In the accompanying drawings; Figure 1 is a view of the lock showing the rear or outer face of the casing removed and the bolts in their retracted or unlocking position; Fig. 2 is a similar view showing the bolts projected; Fig. 3 is a view in horizontal section showing the bolts retracted; Fig. 4 is a similar view showing the bolts projected; Fig. 5 is a view in transverse section 25 of the lock casing and bolt, and Fig. 6 is a view in perspective of the bolt and its tumbler, the latter being shown at one side of the bolt.

10 represents the face plate of a lock 35 adapted to be secured to a door, and 11 is the lock casing secured to the face plate by screws 12 which pass through the front end of the casing and engage threaded openings in the edge flange 13 of the face plate 10.

40 The knob shank 14 is journaled in the lock casing and carries the roll back 15, which when turned, engages the T-shaped end 16^a or tumbler 16, and a shoulder 17 or 17^a on the bolt 18 and shifts the tumbler 16 in a direction to release the main or deadlocking bolt and move the latter from one of its positions to the other.

The knob shank 14 is provided with a 50 cam 19 which is engaged by the spring actuated lever 20 which operates to yieldingly hold the roll back in its normal position out of contact with the tumbler 16 and shoulder 17-17^a of bolt 18.

The bolt 18 is slotted on its front face to 55 receive the roll back 15, and is slotted trans-

versely on its rear face adjacent its rear end for the tumbler 16, as shown in Fig. 6, and it is provided on both faces at the front of the groove for the tumbler with the shoulders 17 which are engaged by the roll back 15 60 on the knob for shifting the bolt to its projected position, and with similar shoulders 17^a at the rear of said slot, the said shoulder at one side of the bolt adapted to be engaged by the roll back, and the shoulders 65 at the opposite side of the bolt are engaged by the cam 21 which latter is connected with the key lock 22 and actuated by the latter in the usual and well known manner, so that the bolt may be projected and retracted by 70 either the knob 23 or by a key entered in the lock 22.

The bolt is further provided on its rear face with a recessed seat for the spring 24 which engages a shoulder 25 on the tumbler 16 75 and operates to yieldingly hold the end 26 of the latter within one of the recesses 27-27^a in plate 28 which is rigidly fixed to casing 11. The tumbler is carried by and moves with the dead locking bolt 18 and has 80 in addition a longitudinal movement transversely of the bolt.

When the latter is in its retracted position as shown in Fig. 1 the locking end 26 of the tumbler 16 rests within recess 27 adjacent the rear end of plate 28, and when the bolt is in its projected position the said tumbler rests within the recess 27^a nearer the outer end of the lock casing.

Pivotedly mounted at the outer end of 90 the casing is the hook shaped bolt 29, which is normally held retracted by the coiled spring 30 and when retracted as shown in Fig. 3, is wholly within the lock casing 11 so as not to interfere with the free opening 95 and closing movements of the door. The main or deadlocking bolt 18 normally rests wholly within the casing 11 with its outer end in contact with or adjacent to the inner faces of the hook shaped bolt 29 as shown 100 in Fig. 3 so that when the dead locking bolt 18 is moved outwardly to its locking position, it turns the hook shaped bolt 29 on its pivots and projects it into the keeper 31 and also follows it into the keeper as shown in 105 Fig. 4 and not only performs the function of an ordinary bolt, but backs up and reinforces the said hook shaped bolt 29. As the hook shaped bolt is turned on its pivots, it enters the keeper and its hook shaped end 32 110

overlaps the latter, so that when the door is locked the hook shaped bolt is positively deadlocked and reinforced by the main bolt 18. The overlapping of the keeper by the hook shaped end 32 of the bolt 29, locks the two parts against separation, hence when the door is locked there can be no separation of the lock from the keeper by a jimmy or other tool introduced between the door and the jamb, or between the lock and the keeper.

In the operation of the lock by a key or by the knob, the cam or the key mechanism, or the roll back or the knob mechanism first engages the T-shaped head of the tumbler 16 and shifts the latter endwise to disengage it from the fixed plate 28, thus freeing the main or deadlocking bolt 18 and permitting it to be projected or moved outwardly by the engagement of the roll back 15 or the cam 21 with a shoulder 17 on the bolt. As the bolt moves outwardly it engages the hook shaped bolt 29 and turns it on its pivot until it is out of the path of movement of the bolt 18, and when in such position its hook 32 overlaps the keeper 31 thus positively connecting the latter with the lock so that there can be no separation of the keeper from the lock. When the main bolt 18 has been fully projected, the end 26 of the tumbler 16 enters the recess 27^a in the fixed plate 28 and thus locks the bolt 18 against movement except by its key or knob mechanism, and as the bolt 18 rests against and reinforces the hook shaped bolt, it follows that the latter cannot be disengaged from the keeper without first retracting the bolt 18. As the bolt 18 is withdrawn or retracted by its knob or key mechanism, the hook shaped bolt will be retracted by its spring 30 which latter holds it yieldingly housed in the casing 11. The hook shaped bolt is moved into locking position by the main bolt 18 and is returned to its normal position by the spring and is not directly actuated by either the knob or the key mechanism.

It is evident that many slight changes might be resorted to in the relative arrangement of parts shown and described without departing from the spirit and scope of my invention, hence I would have it understood that I do not wish to confine myself to the exact construction and arrangement of parts shown and described but,

Having fully described my invention what I claim as new and desire to secure by Letters-Patent, is:—

1. In a lock, the combination of a keeper, a lock casing, a hook shaped bolt normally retained within the lock casing and adapted when projected to interlock with the keeper, and a positively actuated main bolt adapted to force said hook shaped bolt to

locking position and enter the keeper and perform the function of an ordinary sliding bolt and also back up and reinforce the hook shaped bolt. 65

2. In a lock, the combination of a keeper, a lock casing, a hook shaped bolt, a spring for normally retaining the said bolt within the casing, the said hook shaped bolt adapted when projected to interlock with the keeper, and a positively actuated main locking bolt adapted to force the hook shaped bolt to locking position and reinforce it while in 75 such position.

3. In a lock, the combination of a casing, a hook shaped bolt pivoted to the casing and adapted to be projected by a main bolt, a main bolt adapted to reinforce and back 80 up the hook shaped bolt and a tumbler carried by the main bolt and adapted to lock the latter in its two positions.

4. In a lock, the combination of a keeper, a lock casing, a hook shaped bolt, a spring 85 for normally retaining the latter within the lock casing, a main locking bolt for projecting the hook shaped bolt and for reinforcing it when projected and a tumbler mounted in the main bolt and adapted to move transversely of the latter and fixed means engaged by said tumbler for locking the main bolt in its two positions. 90

5. In a lock, the combination of a keeper, a casing a hook shaped bolt, a spring tending 95 to normally hold the said bolt within the casing, a sliding bolt adapted to engage the hook shaped bolt and move it into locking position and reinforce it when in such position, a tumbler carried by the bolt and movable transversely to the latter, fixed means to be engaged by said tumbler for locking the sliding bolt in its two positions and knob mechanism for actuating the tumbler to release the sliding bolt and for shifting the 100 latter. 105

6. In a lock the combination of a keeper, a lock casing, a pivoted hook shaped bolt normally held within the lock casing by a spring and adapted to be projected by a 110 sliding bolt, a sliding bolt adapted to engage the hook shaped bolt for moving the latter into engagement with the keeper and for reinforcing it when in such position, a tumbler for locking the sliding bolt in its 115 two positions and key actuated means for actuating the tumbler to release the sliding bolt and for shifting the latter.

In testimony whereof, I have signed this specification in the presence of two subscribing witnesses. 120

ALFRED C. O. BOCK.
